Primary Examiner — Sharon S Oum(74) *Attorney, Agent, or Firm* — McGarry Bair PC(57) **CLAIM**

The ornamental design for a ceiling fan light kit, as shown and described.

DESCRIPTION

FIG. 1 is a top perspective view of a ceiling fan light kit, showing my new design;

FIG. 2 is a bottom perspective view thereof;

FIG. 3 is a top view thereof;

FIG. 4 is a bottom view thereof; and,

FIG. 5 is a front side view thereof.

The broken lines illustrate portions of the ceiling fan light kit. None of the broken lines form part of the claimed design.

1 Claim, 3 Drawing Sheets(56)
